Primary Examiner — Kelley Donnelly(57) **CLAIM**

The ornamental design for a tray with an interlockable bowl, as shown and described.

DESCRIPTION

FIG. 1 is a top perspective view of a tray with an interlocking bowl as shown;

FIG. 2 is a top plan view thereof;

FIG. 3 is a left side elevational view thereof; the right side elevational view would be a mirror image thereof;

FIG. 4 is a front elevational view thereof;

FIG. 5 is a rear elevational view thereof;

FIG. 6 is a top perspective view thereof, showing the bowl separated from the tray;

FIG. 7 is a top plan view thereof;

FIG. 8 is a front elevational view thereof;

FIG. 9 is a rear elevational view thereof;

FIG. 10 is a left side elevational view thereof;

FIG. 11 is a right side elevational view thereof;

FIG. 12 is a bottom plan view; and,

FIG. 13 is a bottom perspective view thereof.

The broken lines depict environmental subject matter only and form no part of the claimed design.
